UNITED STATES PATENT OFFICE.

EDMUND DAVID BURKITT, OF LONDON, ENGLAND.

CUP-AND-BALL JOINT.

SPECIFICATION forming part of Letters Patent No. 653,728, dated July 17, 1900.

Application filed January 31, 1899. Serial No. 704,014. (No model.)

To all whom it may concern:

Be it known that I, EDMUND DAVID BURKITT, a subject of the Queen of Great Britain, and a resident of Kentish Town, London, in the county of Middlesex, England, have invented certain new and useful Improvements in Cup-and-Ball Joints, of which the following is a full, clear, and exact specification.

This invention relates to improvements in or relating to ball-and-socket joints; and it consists in providing a valve in one of the sections of the joint so arranged that when the joint is separated the supply of gas, in the case of a gas-bracket, is cut off.

For purposes of illustration I will now refer to the annexed drawings, in which—

Figure 1 is a sectional elevation showing the parts forming the joint detached; Fig. 2, a sectional elevation showing the parts forming the joint when in position or engagement; Fig. 3, a side elevation to reduce scale, showing my invention in position; Fig. 4, a plan view of Fig. 2; Fig. 5, a side elevation showing a pipe provided with a series of cups and valves.

Referring to Figs. 1 and 2, the cup *e* is provided with the valve *f*, which is maintained against the seating by means of the spring *g*, which bears upon the carrying socket-piece *i*. This cup *e* is secured on the required pipe in any convenient manner, such as by means of the screw-thread *h*. The valve *f* is of a size to project, as shown, into the cup. The ball *a* is provided with the perforations *d*, which communicate with the passage *b*, and to this ball *a* the required article, such as a bracket, is secured by means of the screw-thread *c* or other suitable arrangement. The weight of the parts—that is to say, the ball *a* and bracket, &c.—and the strength of the spring *g* are in such a relation to one another that when the ball *a*, carrying the required bracket, is placed in the cup *e* the spring *g* is overcome and the valve *f* is thus opened, and

the gas may pass through the joint to the point 45 of combustion. At the same time a joint is formed between the ball *a* and the cup *e*. By this arrangement it will be seen that in the case of a pipe, as shown in Fig. 5, having a series of cups and valves arranged thereon a 50 bracket may be placed in the required position—that is to say, the ball *a*, carrying the bracket, may be removed from cup to cup, as required. When the ball *a* is removed from the cup *e*, the spring *g* raises the valve *f*, and 55 so closes the aperture to the passage of the gas.

Although for purposes of illustration I have shown my invention as arranged so that the valve is carried in the cup, it will be readily 60 understood that, if desired, the valve may be so arranged as to be carried in the ball; but this is a matter of detail.

Having thus described my invention, what I claim, and desire to secure by Letters Patent, is—

In joints of the class herein described in combination, a cup in connection with the gas-supply a spring-valve carried in said cup and having a projection into the interior, a ball having perforations and in connection with the outlet, said ball and outlet branch or parts being of sufficient weight to depress the spring-valve aforesaid and allow of the passage of the gas to the outlet or point of 70 consumption, said cup and ball being adapted to fit one another sufficiently tight for the prevention of the escape of gas, substantially as described and illustrated herein and for the purpose set forth.

In testimony that I claim the foregoing I have hereunto set my hand this 6th day of December, 1898.

EDMUND DAVID BURKITT.
